[57] CLAIM

The ornamental design for an electric air conditioner for electronic enclosures, substantially as shown and described.

DESCRIPTION

FIG. 1 is a perspective view of an electric air conditioner for electronic enclosures, showing my new design;

FIG. 2 is a front elevational view thereof, the rear being plain and unornamented;

FIG. 3 is a left side elevational view thereof;

FIG. 4 is a right side elevational view thereof;

FIG. 5 is a top view thereof;

FIG. 6 is a bottom view thereof.

FIG.1

FIG. 5

FIG. 3

FIG. 2

FIG. 4

FIG. 6
